UNITED STATES PATENT OFFICE.

CHARLES VALLONE, OF BUFFALO, NEW YORK, ASSIGNOR TO BARCALO MANUFACTURING COMPANY, OF BUFFALO, NEW YORK.

SLIDING-SIDE FOLDING CRIB OR BED.

No. 845,384.

Specification of Letters Patent.

Patented Feb. 26, 1907.

Application filed October 23, 1906. Serial No. 340,133.

To all whom it may concern:

Be it known that I, CHARLES VALLONE, a citizen of the United States, residing at Buffalo, in the county of Erie and State of New York, have invented a new and useful Improvement in Sliding-Side Folding Cribs or Beds, of which the following is a specification.

This invention relates more particularly to 10 sliding-side folding cribs or bedsteads.

Cribs are ordinarily provided with side frames which can be secured in a normal raised position, in which they serve to confine the child in the crib, and can be lowered 15 from this position to lessen the exertion of lifting the child into and out of the crib or to enable the crib to be placed alongside of a bed without an intervening barrier between the child and the occupant of the bed. In 20 some cribs the sides are hinged to swing outwardly and downwardly from the normal raised position; but this construction is objectionable, as considerable space is required at the sides of the crib when raising and lowering the side frames, thus making it impossible 25 to operate the side frame while the crib is near to a wall, bed, or other object. That other type of crib in which the side frames slide vertically up and down into and out of 30 the operative raised position is therefore the most desirable.

The primary object of this invention is to produce a crib which can be folded into compact form when not in use or for moving it 35 from place to place and in which the side frames will slide vertically up and down when the crib is set up.

Another object of the invention is to make a folding crib of this sort of a light, strong, 40 stable, and durable construction which can be manufactured at the minimum cost.

Still another object of the invention is to improve the construction of folding cribs in the respects hereinafter described, and set 45 forth in the claims.

In the accompanying drawings, consisting of three sheets, Figure 1 is a side elevation of a crib embodying the invention, showing the side frames raised. Fig. 2 is a similar view 50 thereof, showing the side frames lowered. Fig. 3 is a transverse sectional elevation thereof in line 3-3, Fig. 1. Fig. 4 is a bottom plan view of the crib folded. Fig. 5 is a side

elevation of the crib folded. Fig. 6 is an end elevation of the crib folded. Fig. 7 is a fragmentary sectional elevation showing the position of the hinge-links for the end frames when the crib is folded. Fig. 8 is a fragmentary sectional plan view showing the position of the hinge-links for the end frames when the crib is folded. Fig. 9 is a fragmentary side elevation, on an enlarged scale, showing one of the guide-brackets for the side frames. Fig. 10 is a sectional plan in line 10-10, Fig. 9. Fig. 11 is a transverse sectional elevation in line 11-11, Fig. 9, showing the position of the parts when the side frame is raised. Fig. 12 is a similar transverse sectional elevation showing the folded position of the side frame and guide-bracket. Fig. 13 is a sectional elevation in line 13-13, Fig. 11, showing one of the latches for the guide-brackets.

Like letters of reference refer to like parts in the several figures.

A represents the bottom frame, B B' the end frames, and C C' the side frames, of a crib. These frames are preferably made of metal and may be of any suitable construction. The bottom frame shown consists of angle-bar side rails a, rigidly connected by similar end rails a'. This frame, together with the usual woven-wire or other suitable yielding surface (not shown) supported thereby, constitute the crib-bottom. The end frames shown are of ordinary construction, and the side frames preferably consist of the usual upper and lower horizontal rods c, connected by upright rods c'. The end frames are hinged to the bottom frame, so that they can be swung beneath the bottom parallel therewith, as shown in Fig. 5, by links D D' of different length, pivoted at their opposite ends to the side columns of the end frames and side rails of the bottom frame. When the crib is set up for use, as shown in Figs. 1 and 2, the angle-bar side rails of the bottom rest upon the shorter upper links D, and the longer links D' form inclined braces between the bottom and end frames, so that the parts are held rigid. The links enable the end frames to be swung under the bottom, as indicated by broken lines in Fig. 1, to the folded position shown in Fig. 5, in which they are substantially parallel with the bottom, one being with the other. This manner of hinging the end frames is known; but in the

construction shown the links are offset inwardly at *d*, near their connections with the bottom rails, as shown in Figs. 4 and 8, while their outer ends lie close beside the 5 columns of the end frames, and by reason of this arrangement the links for one end frame will pass inside of or between the links for the other end frame when folding the crib, and will thus allow the end frames to lie flat, one 10 upon the other beneath the bottom, as shown in Figs. 5, 6, and 7, no matter which end frame is folded under first. This is desirable, as persons unskilled in mechanical constructions can properly fold the same without 15 instruction or loss of time. In so far as the other features of the crib about to be described are concerned the end frames could be connected to the bottom in any other manner which would enable them to fold 20 under the bottom.

E represents movable or pivoted guides or brackets connecting the side frames to the bottom, so that they can slide vertically and can also be folded or turned inwardly over 25 the bottom. There are four of these guide-brackets, one at each corner of the crib. In the construction shown (see especially Figs. 9-12) the guide-brackets have upright arms provided at their upper and lower ends with 30 perforated lugs *e*, through which the end upright rods *c* of the side frames pass and in which they are adapted to slide, and each guide-bracket has an inwardly-projecting horizontal arm *e*², provided at its inner end 35 with a depending portion or extension, which passes through a slot *f* in the adjacent end rail of the bottom frame. A lateral lug or enlargement *f'*, Figs. 11 and 12, on the arm prevents the disengagement of the arm from 40 the slot *f*. When the crib is set up for use, the horizontal arms of the guide-brackets lie horizontally on the end rails of the bottom, while their upright arms stand vertically between the side columns of the end frames 45 outside of the side rails of the bottom, as shown in Figs. 9 and 11. In this position of the brackets their horizontal arms will bear on top of the end rails of the bottom, and their lugs *f'* will bear against the under sides 50 of said end rails, so that the brackets will be held steady. The side frames can then be easily slid vertically up and down in the brackets, as described, the same as in the ordinary non-folding sliding-side crib. The 55 horizontal arms can rock or turn in the slots *f* in the bottom end rails, so that the brackets, with the side frames, can be turned or folded inwardly over the bottom, as shown in Figs. 5, 6, and 11. When the side frames 60 are thus folded over the bottom, the horizontal arms of the guide-brackets can slide vertically in their slots *f*, thereby permitting either side frame to be turned in beneath the other and also allowing the side frames to 65 drop down flat on the bottom when the mat-

tress and bedding are removed or to be folded over horizontally on top of the mattress and bedding if it is not desired to remove these from the crib.

The guide-brackets constructed and connected to the bottom as described produce a desirable and inexpensive construction; but the brackets could be differently constructed and otherwise connected to the crib, so that they can be folded inwardly or turned inwardly and raised and lowered, as explained.

Any suitable means can be employed for securing the side frames in the operative raised position. As shown, the projecting ends of the top bars of the side frames are 80 notched at *g* and adapted to interlock with socket-pieces *g'* on the upper portions of the end frames. (See Figs. 1, 2, and 5.) When the side frames are engaged with the sockets, the end frames will be tied together at their 85 upper ends, and the crib as a whole will be rigid and steady. If desired, latches can be employed for holding the guide-brackets stationary or from swinging when sliding the side frames vertically therein. A latch for 90 this purpose is shown at *H* in Figs. 9-13, consisting of a spring-hook projecting up from the end rail of the bottom and adapted to snap over the horizontal arm of the guide-bracket. Any other suitable kind of latch 95 could be employed. Latches can also be used, if desired, to lock the side frames from sliding in the guide-brackets when the crib is to be folded. The latches shown are pivoted to the upright arms of the guide-brackets 100 and have hooks or slotted ends *i*, adapted to swing beneath the ends of the upright arms of the brackets and engage under collars *i'* on the end upright rods of the side frames. Before folding in the side frames over the 105 bottom the latches are engaged under the collars, as shown in Fig. 12, and they will then prevent the side frames from slipping down in the brackets when holding the crib. These latches or other means for the same purpose 110 can be employed or not, as found expedient.

In the crib described the side frame can be raised and lowered vertically when the crib is set up just as in the ordinary sliding-side non-folding cribs; but in addition they can 115 be folded or turned inwardly and downwardly over the crib-bottom either directly thereon or at a sufficient distance above the bottom to accommodate the mattress and bedding.

I claim as my invention—

1. In a crib or bed, the combination of a bottom, side frames, and connections between said side frames and the crib structure constructed to allow said side frames to slide vertically and also to fold inwardly substantially parallel with said bottom, substantially as set forth.

2. In a crib or bed, the combination of a bottom, and side frames connected to the crib structure to raise and lower in a vertical

plane and also to fold inwardly over the bottom, substantially as set forth.

3. In a crib or bed, the combination of a bottom, side frames, and guide devices on which said side frames are movable up and down vertically and which are movable to fold said side frames inwardly substantially parallel with said bottom, substantially as set forth.

10 4. In a crib or bed, the combination of a bottom, guide-brackets hinged to said bottom to swing inwardly over the same, and side frames which slide vertically on said guide-brackets, substantially as set forth.

15 5. In a crib or bed, the combination of a bottom, side frames, guide-brackets on which said side frames slide vertically and which are connected to said bottom to swing inwardly over the same and also to fall and rise 20 toward and from the bottom, whereby the side frames can lie horizontally close to the bottom or at a distance above the bottom, substantially as set forth.

25 6. In a crib or bed, the combination of a bottom, guide-brackets having horizontal arms hinged to said bottom and upright arms with guide-openings at their upper and lower ends, and side frames having vertical rods which slide in said guide-openings, substantially as set forth.

30 7. In a crib or bed, the combination of a bottom, guide-brackets having horizontal arms connected to said bottom to swing and move toward and from said bottom, and upright guide-arms, and side frames which slide

vertically on said upright arms, substantially as set forth.

8. In a crib or bed, the combination of a bottom, side frames, guide devices on which said side frames are movable up and down vertically and which are movable to fold said side frames inwardly substantially parallel with said bottom, and means for releasably holding said guide devices in normal position, substantially as set forth.

40 9. In a crib or bed, the combination of a bottom, side frames, guide devices on which said side frames are movable up and down vertically and which are movable to fold said side frames inwardly substantially parallel with said bottom, and means for releasably holding said side frames from movement on said guide devices, substantially as set forth.

45 10. In a crib or bed, the combination of a bottom, end frames at opposite ends of said bottom, and swinging links connecting said end frames and bottom whereby said end frames can be folded one beneath the other substantially parallel with the bottom, said links for each end frame having offset portions at or near one end to allow the links for either end frame to move between the links for the other end frame, substantially as set forth.

50 Witness my hand this 13th day of October, 1906.

CHARLES VALLONE.
